GESELLSCHAFT BROWN BOVERI & CIE., OF BADEN, SWITZERLAND

VAPOR RECTIFIER

Application filed July 2, 1925, Serial No. 41,128, and in Germany August 8, 1924.

Vapor rectifiers constructed of metal are frequently subject to transitory and quite short-lived flashing over which is generally terminated by the sudden cutting out of the arc in the defective phase. Such sudden interruptions in the current cause an excess of potential in the inductances of the anode circuit with the result that the insulation of the rectifier installation is subjected to great stress and may be easily damaged. If, in addition, sparking occurs from anode to anode a further flashing over of a more violent nature may be started. It is important therefore to provide means for preventing 15 sparking from anode to anode by limiting the excess of potential to an amount that involves no risk. Exhaustive experiments have shown that when excess of potential occurs the metal container of the rectifier always assumes the potential of the normally working anodes, whilst the defective anode, i.e., the anode which has been acting as a cathode during the transitory flashing back, shows a high potential as compared with the 25 metal container.

This invention consists of means for preventing excessive potential differences as between electrodes in vapor rectifiers constructed of metal, and in accordance therewith several paths for the current are provided between the circuits of the several electrodes and the metal container of the rectifier, such paths containing spark gaps and ohmic resistances. The spark gaps are preferably adjusted for an excess of potential which is less than the value of the potential permissible for the insulation of the installation. The effect of this arrangement is that no dangerous excess potential difference can occur since even a slight rise will cause a spark discharge between the circuit of the affected electrode and the metal container, the electrical energy of the spark being dissipated in the ohmic resistance.

Referring to the drawing, which is a diagrammatic representation of a rectifier and circuits, N denotes a single-phase circuit, and T the transformer that feeds the rectifier G, P being the primary winding of the transformer and the secondary winding comprising

the halves Q¹ and Q². The outer terminal of the winding Q¹ is connected to the anode A¹ and the outer terminal of the winding Q² to the anode A². D represents the cooling dome and K the cathode of the rectifier. The load V is connected between the cathode K and the common terminal of the windings Q¹ and Q². The anode A¹ is connected through the resistance W¹ and the spark gap F¹ to the metal container G. Similarly, the anode A² is connected through the resistance W² and the spark gap F² to the metal container G, and the cathode K is connected through the resistance W³ and the spark gap F³ to the metal container G. With this arrangement it is immaterial which of the electrodes assumes a high potential, since there will always be a sufficiently early discharge to the metal container to prevent its reaching a point of danger. Thus the limit for the potential which an electrode may reach can be fixed beforehand by the adjustment of the spark gap.

This arrangement can be used also with advantage in the case of polyphase rectifiers.

What I claim is:—

1. In vapor apparatus for rectifying alternating current, an insulated metal container, electrodes disposed in said metal container and insulated therefrom, and a spark gap and an ohmic resistance connected between each electrode and the metal container.

2. In a system for rectifying alternating current, an alternating current supply, a metal vapor rectifier comprising a metal container and electrodes disposed in the latter and insulated therefrom, transformer means connecting said rectifier to said supply in rectifying relation with respect thereto, and means responsive to conditions tending to produce a predetermined potential difference between certain of said electrodes and being operable at substantially such conditions to provide an electrostatic discharge circuit between the electrode of higher potential and said container.

3. In a system for rectifying alternating current, an alternating current supply, a metal vapor rectifier comprising a metal

- container and electrodes disposed in the latter and insulated therefrom, transformer means connecting said rectifier to said supply in rectifying relation with respect thereto, and means responsive to conditions tending to produce a predetermined potential difference between certain of said electrodes and being operable at substantially such conditions to provide an electrostatic discharge circuit between the electrode of higher potential and said container, said last-named means including a discharge gap and a resistance in series therewith.
4. In apparatus of the sort described, the combination with the rectifier casing, anodes and anode supply windings, of a spark gap and ohmic resistance providing an excess-voltage shunt between the casing and supply windings.
5. In apparatus of the sort described, the combination with the rectifier casing and electrodes, of a spark gap and ohmic resistance providing an excess-voltage shunt between the casing and electrodes.
6. In apparatus of the sort described, the combination with the rectifier casing and electrodes, of a spark gap and ohmic resistance providing an excess-voltage shunt between the casing and respective electrodes.
- 30 Dated this 16th day of June, 1925.
ERWIN KERN.
